HAIR ROLLER

Patrick R. Jeronimus, Park Forest, Ill., assignor to The Gillette Company, Boston, Mass., a corporation of Delaware

Filed Nov. 28, 1966, Ser. No. 4,835

Term of patent 14 years

(Cl. D86—10)

FIG. 2

FIG. 1 is an isometric view of a hair roller showing my new design;

FIG. 2 is a developed plan view showing the entire cylindrical surface of the roller of FIG. 1.

The drawing is lined for color without indicating specific colors.

I claim:

The ornamental design for a hair roller, as shown and described.
